UNITED STATES PATENT OFFICE.

WALLACE BOARDMAN, OF HARRISONVILLE, MISSOURI.

HAME-TUG.

SPECIFICATION forming part of Letters Patent No. 392,306, dated November 6, 1888.

Application filed November 29, 1887. Renewed October 11, 1888. Serial No. 287,858. (No model.)

To all whom it may concern:

Be it known that I, WALLACE BOARDMAN, of Harrisonville, in the county of Cass and State of Missouri, have invented a new and Improved 5 Hame-Tug for Harness, of which the following is a full, clear, and exact description.

My invention relates to a hame-tug made partly of metal and partly of leather, and so constructed as to form a practical hame-tug with 10 less leather than is used in the common hame-tug, and whereby either the front or rear part of the tug, if broken or worn, may be removed without throwing the other away, and if one section should be worn out it can be replaced 15 without opening the whole tug.

Reference is to be had to the accompanying drawings, forming a part of this specification, in which similar letters of reference indicate corresponding parts in all the figures.

20 Figure 1 is a side elevation of my new and improved hame-tug, showing the end of the trace held in the hame-tug buckle. Fig. 2 is a longitudinal sectional elevation of the hame-tug, and Fig. 3 is an enlarged transverse sectional elevation taken on line $x x$ of Fig. 2.

25 I construct my new hame-tug in two sections, A B. The section A is composed of the plate C, of metal, and the leather straps D D, secured one upon each side of said plate by rivets $a a$. The rear end of the plate C is formed with the cheek-pieces $d d$ and curved bridge d' , which forms a seat for the hinge-eye f of the plate E, below described. The cheek-

pieces d are perforated to receive the hinge screw or bolt F, and are formed also with the 35 loop or billet-keeper G to hold the front end of the traces H.

The rear section, B, of the hame-tug is composed of the said metal plate E and the straps J J, of leather, secured one upon each side of the 40 said plate by the rivets $c c$. The front end of the said plate E is formed with the said hinge-eye f , and the eye is formed at its ends with the stop-shoulders $h h$, which strike against the edges of the curved bridge d' , and thus 45 limit the hinge or folding motion of the tug.

The tug is provided at its rear end with the buckle L for holding the trace, and at the forward end with the eye M for connecting the hame-tug to the hame. (Not shown.) 50

Having thus described my invention, what I claim as new, and desire to secure by Letters Patent, is—

1. The plate C, having the perforated cheek-pieces d , formed with a billet-keeper or loop, 55 G, in combination with the plate E, hinged to the plate C, substantially as described.

2. The hame-tug herein described, provided with the plate C, formed with the cheek-pieces $d d$ and curved bridge d' , in combination with 60 the plate E, formed with the hinge-eye f and stop-shoulders h , substantially as described.

WALLACE BOARDMAN.
